UNITED STATES PATENT OFFICE.

FREDERICK H. AULD, OF COLUMBUS, OHIO, ASSIGNOR TO THE D. L. AULD COMPANY,
OF COLUMBUS, OHIO.

METHOD OF DECORATING METAL PLATES.

Application filed August 24, 1925. Serial No. 51,986.

To all whom it may concern:

Be it known that I, FREDERICK H. AULD, a citizen of the United States, residing at Columbus, in the county of Franklin and 5 State of Ohio, have invented certain new and useful Improvements in Methods of Decorating Metal Plates, of which the following is a specification.

The present invention is directed to a 10 method of decorating metal plates.

The primary object of the invention is to provide a method wherein metal plates can be decorated with wood veneer of different colors and when so decorated will be 15 extremely attractive and may be used for various purposes.

A further object of the invention is to provide a method wherein wood veneer varying in color can be easily and quickly 20 secured to the plate to form a permanent part thereof.

In the drawing:—

Figure 1 is a plan view of the plate.

Figure 2 is a sectional view showing the 25 sheet previous to applying pressure thereto.

Figure 3 is a similar view after pressure has been applied.

Figure 4 is a similar view parts of the 30 sheet removed.

Figure 5 is a similar view showing the position of the second sheet before applying 35 pressure thereto.

Figure 6 is a similar view after pressure has been applied to the second sheet.

Figure 7 is a sectional view on line 7—7 40 of Figure 1.

In carrying out my method I employ a metal plate 1, which may be produced in any suitable manner to provide the plate 40 with a marginal wall 2 and a resultant recess 3. The base of the recess is provided with walls 4, in this instance rectangular in contour so as to provide recesses 5. The upper edges of the walls 4 are in a plane 45 with the upper edges of the wall 2. To decorate the plate it is necessary that veneer of contrasting colors be secured in the respective recesses and in order to accomplish this I first take a sheet of veneer of maple, 50 designated by the numeral 6 and place it upon the plate 1, as shown in Figure 2 of the drawing, and after the recess 3 has been coated with suitable cement, and at this step of the method care being taken that no

cement enters the recesses 5. The sheet 6 55 is then subjected to pressure in any approved manner so that it will be pressed into the recesses 3 and 5 and it assumes the position as shown in Figure 3 of the drawing and at which time the walls 2 and 4 form impressions 60 7 and 8, respectively, in the sheet. To remove these impressions, as well as the portions of the sheet resting upon the wall 2, a grinder of any approved design is employed which removes all portions of the 65 sheet above the upper edges of the respective walls, as shown in Figure 7 of the drawing, which leaves all of the recesses filled with portions of the sheet.

After this grinding operation it is necessary that the pieces of veneer occupying the recesses 5 be removed in order to make room for veneer contrasting in color to the sheet 6, which as before mentioned is maple, a comparatively white colored wood. It 70 has been found that upon jarring the plate 1 that the veneer occupying the recesses 5 can be readily dislodged owing to the fact that no cement has been placed therein. Owing to the application of cement 75 to the recess 3 the veneer will be firmly retained therein, but is removed from the recesses 5, as shown in Figure 4 of the drawing. I next take a sheet of veneer 80 9, for instance of mahogany or other wood contrasting in color to the sheet 6, and place it upon the plate, as shown in Figure 5 of the drawing, said sheet then being subjected to pressure in the same manner as the sheet 6, it being of course understood that 85 the recesses 5 have now been coated with cement. After pressure has been applied to the sheet 9 it assumes the position as shown in Figure 6 of the drawing. The sheet 9 is then subjected to the action of the grinder in order to remove all parts of said 90 sheet above the plane of the upper edges of the walls 4 defining the recesses 5, thereby filling the recesses 5. In this manner 95 the recesses 5 as well as the recess 3 are filled with sections of veneer, as shown in Figure 7 of the drawing.

Since the sheets 6 and 9 are of contrasting colors the effect will greatly enhance 100 the appearance of the plate and it will be of course understood that in lieu of the walls 4 other configurations may be used, such for instance as society emblems, crests
